UNITED STATES PATENT OFFICE.

JOHN KELLY WEDGWORTH, OF CUBA, ALABAMA.

RAIL TIE AND FASTENING.

Application filed January 9, 1922. Serial No. 527,923.

To all whom it may concern:

Be it known that I, JOHN K. WEDGWORTH, a citizen of the United States, residing at Cuba, in the county of Sumter and State of Alabama, have invented certain new and useful Improvements in Rail Ties and Fastenings; and I do declare the following to be a full, clear, and exact description of the invention, such as will enable others skilled 5 in the art to which it appertains to make and use the same.

This invention relates to an improved metal rail tie and fastening.

The principal object of the invention is 15 to generally improve upon ties and fastenings of this class by providing a practical device which is composed of comparatively few parts of extreme simplicity and durability, thus providing a structure which permits the tracks to be easily and readily laid 20 and enables the cost of manufacture to be reduced to a minimum.

Another and important object of the invention is to improve upon my Patent 25 1,399,909 granted to me on December 13, 1921.

By briefly reviewing the above named patent it will be seen that the same includes among other details, a metal rail tie of 30 channel-shaped cross-section having in-turned rail supporting flanges braced by blocks arranged between the vertical side walls of the tie and engaging the under sides of said flanges, these blocks carrying 35 jaws designed to grip the base flanges of the rail and there being special means for maintaining the jaws in engagement with the rail flanges.

I aim to eliminate the special means for 40 maintaining the blocks in effective position and simply substitute novel co-acting means between the blocks and rail supporting flanges.

Another improvement embodied in the 45 present case and not set forth in the patented tie and fastening is a novel rail clamp which permits effective use of the invention at switch points and at points where guard rails and the like are positioned.

50 Other objects and advantages of the invention will be apparent during the course of the following description.

In the accompanying drawings forming a part of this specification and in which like

numerals are employed to designate like parts throughout the same:

Figure 1 is a top plan view of a conventional form of railroad rail showing a switch and the manner in which the improved rail tie and fastening co-acts with the rails. 60

Figure 2 is an enlarged perspective view of the tie showing the fastening members and rails more clearly.

Figure 3 is a detail perspective view of the rail clamps removed. 65

Figure 4 is a detail perspective view of a slightly different form of clamp used at switch points.

Figure 5 is a perspective view of one end of the tie showing the slit flanges before being bent. 70

Figure 6 is a view like Fig. 5 showing portions of the rail supporting flanges bent for co-action with the rail flange.

Referring to the drawings in detail, the 75 numeral 1 designates a metal tie of channel-shaped cross section, the same being open at its opposite ends and the spaced vertical walls thereof having their upper portions directed inwardly toward each other to provide opposed rail supporting flanges 2. Slidably mounted between the vertical sides of the tie are blocks 3 provided on their upper sides with reduced integral extensions 4 formed with notches 5. These notched extensions constitute jaws which are designed 80 to engage the base flanges of the rails R. It will be noted that the blocks are arranged close to one another on opposite sides of the rails when in use and the blocks are of 85 a height to engage the under sides of the rail supporting flanges. Consequently, they brace 90 these flanges and prevent them from bending under the weight of the rails which rest on their upper sides and extend cross-wise 95 thereof.

So far as the description has gone, it sets 100 forth a tie and fastening members which are substantial duplicates of the corresponding parts disclosed in the aforesaid patent with the exception that the tie here shown is open at its opposite ends, instead of being closed, to permit insertion and removal of the blocks. As before pointed out, it is one of the particular aims to provide novel 105 means for maintaining the blocks immovable so that the jaws will effectively engage and hold the rails against accidental sepa-

ration and movement. In order to provide extremely simple means for accomplishing this end, I simply slit the rail supporting flanges 2 at opposite points as indicated at 5 6. Then, I form the blocks 3 in their upper sides with comparatively shallow recesses 7 and thereby provide shoulders. After the blocks are slid between the side walls of the tie and the jaws positioned for engagement 10 with the opposite sides of the base flanges of the rails as shown clearly in Fig. 2, I then bend portions of the rail supporting flanges inwardly as indicated at the points 8 so that these bent portions extend into the recesses 7 and abut the shoulders formed thereby. Consequently, the blocks are thus held against separation, but are capable of being easily and readily removed by simply inserting a suitable instrument between their upper 15 sides and the bent portion 8 of the flanges to straighten the bent portions so that the blocks can be slid through the open ends of the ties.

At the points of the track where switches, 20 guard rails and the like occur, I find it advisable to utilize a slightly different form of clamp such as shown in Fig. 4. The clamp here shown likewise comprises a rectangular or square block 9 formed on its upper side with a reduced rib 10 having notches 11 formed at its opposite ends to provide jaws for engaging the base flange of one of the straight and curved rails respectively as indicated in Fig. 1. By directing attention to the last mentioned figure it will be seen that these differently constructed clamps will vary considerably in length according to their position. It will also be understood more clearly after viewing this figure that the notch at one 25 end of the rib 10 is designed to engage one edge of the base flange of the straight rail while the notch at the opposite end is designed to engage the corresponding part of the curved rail of a switch. In cases where 30 guard rails occur and are in parallelism with the main rails, the special clamps need not vary in shape and design. I state "design" because the notches at the ends of the ribs 35 10 will have to be shaped to effectively engage both straight and curved rail flanges.

By carefully considering the description in connection with the drawings, persons familiar with devices of this class will

doubtless be able to obtain a clear understanding of the invention. Therefore, a more lengthy and detailed description is deemed unnecessary.

Since probably the best results may be obtained with the construction and arrangement herein shown and described, this is taken as the preferred embodiment of the invention. However, I wish it to be understood that minor changes coming within the scope of the invention as claimed may be resorted to if desired.

I claim:

1. A rail tie and fastening comprising a tie of channel-shaped cross section having the upper portions of its vertical side walls 70 directed inwardly toward each other to form rail supporting flanges, a pair of rail clamps slideable between the side walls of said tie, said clamps being formed with recesses providing shoulders, the aforesaid rail supporting flanges being formed with shoulders for co-action with the first named shoulders to maintain the clamps in operative position.

2. A rail tie and fastening comprising a channel-shaped tie open at its opposite ends having the upper portions of its side walls directed inwardly toward each other to form rail supporting flanges, the latter being formed with oppositely disposed and closely spaced slits, the portions of the flanges on one side of each slit being bent inwardly to form shoulders, and rail clamps slideable between the vertical side walls of the tie and adapted for disposition on opposite sides of the base flange of the rail, each clamp being formed with spaced depressions forming shoulders with which the aforesaid shoulders are engaged, whereby to maintain the clamps in engagement with the base flanges of the rail.

3. A rail tie of channel-shaped cross-section, said tie being open at its opposite ends and the upper portions of its vertical sides being directed inwardly toward each other to form rail supporting flanges, said flanges being slit inwardly from their inner edges at spaced points and the portions of material on one side of each slit being bent inwardly to form shoulders.

In testimony whereof I have hereunto set my hand.

JOHN KELLY WEDGWORTH.
